UNITED STATES PATENT OFFICE.

ROBERT D. BOOTH, OF PHILADELPHIA, PENNSYLVANIA, ASSIGNOR TO THE PSARSKI
DYEING MACHINE COMPANY, OF CLEVELAND, OHIO, A CORPORATION OF OHIO.

DYEING-MACHINE.

1,113,405.

Specification of Letters Patent.

Patented Oct. 13, 1914.

Application filed October 16, 1911. Serial No. 654,922.

To all whom it may concern:

Be it known that I, ROBERT D. BOOTH, a citizen of the United States, residing at Philadelphia, in the county of Philadelphia and State of Pennsylvania, have invented 5 certain new and useful Improvements in Dyeing-Machines, of which the following is a specification.

In dyeing permeable materials various 10 types of machines have been used and among these is the machine set forth in the patent to John T. Psarski No. 955,993 granted April 26, 1910, and in many of these machines, the paths of travel of the dye liquor 15 established by the inlet and the discharge are of uneven lengths. This is true of the paths of travel set up in the Psarski patent by the openings in the false bottom, and in the dome adjacent to the base of the dome 20 as the distance from this point to the discharge is much greater than it is from the other liquor supply openings in the dome and in the false bottom to the discharge, and this 25 unequal length in the paths of travel of the liquor requires that the machine shall be operated in an extremely careful manner to avoid the splitting of the batch when the liquor flows more readily through one portion than through another.

30 The object of the present invention, therefore, is to provide a construction of dyeing machine wherein the paths of travel of the dye liquor shall converge from the inlet toward substantially the center of the discharge, and whereby they shall be substantially equal whereby a substantially uniform 35 resistance is set up to the dye liquor throughout the entire tank, with the result that an even dyeing of the mass results and the 40 splitting of the batch is avoided.

More specifically the invention relates to a tank or kettle provided with a cover having an annularly disposed group of rows of perforations, and a distributing member 45 within the tank and having a foraminous discharge portion conforming to an arc described about substantially the center of the discharge.

The invention may be still further briefly 50 summarized as consisting in the construction and combinations of parts hereinafter set forth in the following description, drawings and claims.

Referring to the drawings, Figure 1 illus-

trates one form of my invention partly in 55 section; Fig. 2 is a top plan view of a portion of the cover; and Fig. 3 is a top plan view of a portion of the distributing member.

In carrying out the invention any preferred form and construction of parts may be employed so long as they possess the necessary characteristics, but I have shown one form in the drawings which is highly effective in operation, and in such embodiment, 1 60 represents the tank provided with a bottom 2 having an opening 3 therein for receiving a pipe 4 leading to the outlet of a centrifugal pump 5. This pump is connected at its inlet, by means of a pipe 6, with a three-way 70 valve 7 arranged between a pipe 8 leading to an opening 9 in the bottom of the tank, and a pipe 10 leading to an opening 11 in the side of the tank near the top. This piping and pump are for the purpose of establishing a circulation in any direction but during the dyeing operation it is preferable to establish a circulation up through the pipe 4 into the center of the tank. A suitable steam pipe connection 12 may be placed above the 80 bottom of the tank for the purpose of heating the liquor. The inner wall of the tank may be provided with openings 13 for receiving clips 14 for a purpose to be described. The tank is further provided with a shoulder 85 15 at its bottom. Resting upon the shoulder 15 is a distributing member comprising a central portion 16 having an opening for receiving the shank 17 of a bolt 18 which passes up above the top of the machine. This bolt is held in place by a nut 19. This central portion 16 is provided with a downwardly and outwardly extending flange 20 which is curved inward on the downward slope in an arc described about 95 the center of the discharge to be described. This portion 20 rests upon the shoulder 15. Resting upon a gasket 21 on top of the central portion 16 is a cover 22 having an opening 23 at the center for the passage of the bolt 18 and provided near its periphery with 100 rows of openings 24 which form the discharge, and it is the main point between the circle passing through the centers of the inner row of holes and the circle passing through the centers of the outer row of holes which forms the center of the arc described by the foraminous portion 20 of the

distributing member. This cover is engaged by the clips 14 which hold it in place. A suitable nut 25 upon the bolt 18 serves to hold this cover tightly down upon the central portion of the distributing member.

In operation, the material is packed in the annular chamber formed between the distributing member and the side of the tank, the cover is then placed in the machine and secured, and the pump is started with the result that the dye liquor is forced up into the chamber formed within the distributing member, from whence the liquor is directed outwardly from the center and upwardly from the bottom to the discharge, the supply openings in the distributing member being all substantially equidistant from the central point of the discharge. In this way all of the material is evenly dyed by reason of the even length of travel of the liquids in the directions in which it must pass.

Very important features among those produced by the foregoing construction are, first, the fact that the liquor is caused to pass through the entire mass uniformly, and second, in starting the material in all parts of the machine is under substantially the same influence of the dye liquor, that is, a circulation is set up in starting which tends to crowd all portions of the material toward the imperforate areas on either side of the discharge and toward the discharge, thereby doing away with the splitting of the batch, or in other words, preventing the floating of portions of the material on the face thereof adjacent the inlet.

Having described my invention, I claim:—

1. In apparatus for dyeing permeable material by forcing dye carrying liquor through the same, a receptacle forming a chamber for receiving the material to be dyed and having a discharge with an imperforate area on each side thereof, and mass forming and liquor supplying means having liquor distributing openings opposed to the discharge and the imperforate areas, said mass forming and liquor supplying means, said discharge, and said imperforate areas being relatively located to establish substantially equal paths of travel for the dye liquor and to produce a resultant circulation for forcing the material against the imperforate areas and toward the discharge, and means for circulating the dye liquor.

2. In apparatus for dyeing permeable material by forcing dye carrying liquor through the same, a receptacle forming a chamber for receiving the material to be dyed and having a foraminous discharge portion bounded by a non-foraminous portion, and liquor supplying means, each point of liquor inlet thereof being substantially equidistant from its opposed point of discharge and all of said liquor inlets being

substantially in opposition to a non-foraminous portion, and means for circulating the dye liquor.

3. In apparatus for dyeing permeable material by forcing dye carrying liquor through the same, a receptacle forming a chamber for receiving the material to be dyed and having liquor supplying means, also having a foraminous discharge with a non-foraminous zone located between said liquor supplying means and the foraminous discharge and arranged in opposition to the liquor entrance, said discharge being substantially equidistant from all of its opposed points of supply, and means for circulating the dye liquor.

4. In apparatus for dyeing permeable material by forcing dye carrying liquor through the same, a receptacle forming a chamber for receiving the material to be dyed and having a foraminous discharge bounded by a non-foraminous zone, distributing means within the chamber and having its points of liquor supply in opposition to the non-foraminous zone and equidistant from the opposed center of discharge from the receptacle whereby the liquor flowing through different portions of the mass may have substantially the same length of travel and may force the mass against the non-foraminous zone and toward the discharge, and means for circulating the dye liquor.

5. In apparatus for dyeing permeable material by forcing dye carrying liquor through the same, a receptacle forming a chamber for receiving the material to be dyed and having a discharge with an imperforate area on each side thereof, a distributing member within the chamber and having its points of liquor supply equidistant from the opposed center of discharge from the receptacle whereby the liquor flowing through different portions of the mass may have substantially the same length of travel and may force the mass against the imperforate areas and toward the discharge, and means for circulating the dye liquor.

6. Apparatus for dyeing permeable material by forcing dye carrying liquor through the same, comprising a receptacle, a cover for said receptacle having a discharge through the same, distributing means within the receptacle and having its points of liquor supply substantially equidistant from the opposed center of discharge, and means for circulating the dye liquor.

7. Apparatus for dyeing permeable material by forcing dye carrying liquor through the same, comprising a receptacle, a cover for said receptacle having a discharge through the same, a distributing member having a foraminous distributing portion with substantially all of its points of liquor supply substantially equidistant

from the opposed center of discharge, and means for circulating the dye liquor.

8. Apparatus for dyeing permeable material by forcing dye carrying liquor through the same, comprising a receptacle, a cover for said receptacle having a foraminous discharge portion and an imperforate area exposed to the interior of the receptacle, a distributing member within said receptacle and provided with a foraminous distributing portion having substantially all points of its liquor supply equidistant from the opposed center of discharge, and means for circulating the dye liquor.

15 9. Apparatus for dyeing permeable material by forcing dye carrying liquor through the same, comprising a receptacle, a cover for said receptacle having an annular foraminous discharge portion and an imperforate area adjacent thereto exposed to the interior of the receptacle, a distributing member within said receptacle and provided with a foraminous distributing portion having substantially all points of its liquor supply equidistant from the opposed center of discharge, and means for circulating the dye liquor.

10 10. Apparatus for dyeing permeable material by forcing dye carrying liquor through the same, comprising a receptacle, a cover therefor having an annular group of discharge openings arranged near the periphery thereof with an imperforate area within exposed to the interior of the receptacle, a distributing member within the receptacle and provided with a foraminous

portion having substantially all points of its liquor supply equidistant from the opposed center of discharge, and means for circulating the dye liquor.

15 11. Apparatus for dyeing permeable material by forcing dye carrying liquor through the same, comprising a receptacle, a cover for said receptacle provided with a foraminous portion and an imperforate portion exposed to the interior of the receptacle, a distributing member within said receptacle and having a curved foraminous distributing portion substantially every point of which touches an arc described about substantially the center of the opposed point of discharge, and means for circulating the dye liquor.

20 12. Apparatus for dyeing permeable material by forcing dye carrying liquor through the same, comprising a receptacle, a cover therefor having an annular discharge portion near the periphery only, a distributing member within the receptacle and having a foraminous distributing portion curved in cross section from the center to the periphery in an arc described about substantially the central point of the discharge in the cover, and means for circulating the dye liquor.

In testimony whereof I affix my signature in presence of two witnesses as follows.
